Primary Examiner — Kelley A Donnelly(74) *Attorney, Agent, or Firm* — Quarles & Brady LLP(57) **CLAIM**

The ornamental design for a bin assembly, as shown and described.

DESCRIPTION

FIG. 1 is a perspective view of a top, front, and left side of an ornamental design for a bin assembly; and, FIG. 2 is a front elevational view of the bin assembly of FIG. 2, the rear, left, and right side elevational views being identical thereto.

The dash-dash-dash lines are included for the purpose of illustrating portions that form no part of the claimed design.
